ELECTRIC PULSE TRANSLATOR CIRCUIT

Alec Harley Reeves, London, England, assignor to
 International Standard Electric Corporation,
 New York, N. Y., a corporation of Delaware

Application April 17, 1948, Serial No. 21,695
 In Great Britain June 5, 1947

8 Claims. (Cl. 332—9)

1

The present invention relates to electric pulse modulating and demodulating arrangements employing cold cathode gas-filled discharge tubes.

When high signal-to-noise ratio have to be provided in pulse modulators and demodulators, the use of a gas-filled tube sometimes causes trouble on account of the slight irregularities in the moments of firing of the tube, which increase the noise introduced by the modulating and demodulating arrangements.

It is the principal object of the present invention to overcome this difficulty, so that the advantages of using gas-filled tubes in such arrangements may be secured while still conforming with the most stringent noise requirements.

This object is achieved according to the invention by providing an electric pulse channel selector for a multichannel electric pulse communication system having n channels, comprising a cold cathode gas filled electric discharge tube having a sequence of n discharge gaps including an output gap, arranged as a counter tube, means for applying a train of input pulses to the tube in such manner as to fire the gaps in turn, means for deriving from the output gap a pulse corresponding to each n th input pulse, and means for applying the output pulses as gating pulses to render operative the equipment corresponding to a specified channel.

The invention will be described with reference to the accompanying drawings in which:

Fig. 1 shows a schematic circuit diagram of a pulse modulator according to the invention;

Fig. 2 shows curves used in explaining the action of the modulator;

Fig. 3 shows a schematic circuit diagram of a pulse demodulator according to the invention; and

Fig. 4 shows curves used in explaining the action of the demodulator.

Referring to Fig. 1, the discharge tube 1 preferably contains a gas filling of 92% neon, 1% argon and 7% hydrogen at a total pressure of 100 mm./Hg. It includes an anode 2 in the form of a flat plate or wire, a corrugated counting cathode 3 arranged parallel to the anode, and an output plate cathode 4. The tips of the corrugations form with the anode a sequence of discharge gaps, all of which are equal, except the one at the left hand end, which is smaller; and the gap between the cathode 4 and the anode 2 should be equal to the larger gaps. Other forms of cathode could provide the desired sequence of

2

gaps; for example a helical wire, or a metal comb with the teeth projecting towards the anode.

It will be assumed that the circuit of Fig. 1 is one of the channel modulators in a six channel pulse communication system. In that case, the corrugations of the cathode 3 should provide five discharge gaps; if there are n channels, the cathode should provide $n-1$ gaps.

The cathode 3 is connected directly to ground, 10 and the cathode 4 is connected to ground through a network consisting of a condenser 5 shunted by a resistor 6. The anode 2 is connected through a load resistor 7 to the positive terminal of the operating battery 8, the negative terminal of 15 which is grounded.

A train of regularly repeated rectangular pulses as shown in Fig. 2a is applied from a local source (not shown) to terminal 9 which is connected through a blocking condenser 10 to the anode 2.

20 The battery potential should be such that it is insufficient to start any discharge in the tube, but can maintain a discharge when one has been started by other means. The first of the pulses shown in Fig. 2a then fires the small gap at the left hand end of the cathode 3, and the discharge is maintained by the battery after the disappearance of the pulse. The spread of ionisation from the fired gap then primes the next one so that it is fired by the next pulse, and so on, until the

30 sixth pulse fires the gap between the cathode 4 and the anode 2. The discharge spreads over the smooth plate 4 so rapidly that a squeeg is produced in conjunction with the elements 5, 6 and 7, which extinguishes all of the discharges. It is well known that if a large resistance be connected in series with the discharge path of a gas discharge tube, the resistance may limit the discharge current to a value insufficient to produce enough ions to maintain the discharge. However, if the resistance be shunted by a condenser, a discharge can be initiated, which how-

ever very quickly extinguishes itself when the condenser becomes charged. Such a circuit may be arranged in various other ways, and is called for convenience a "squeegging" circuit. The action of the discharge in extinguishing itself is called a "squeeg."

The ion recombination time for the gas should be such that the tube is substantially in its initial unfired condition before the next operating pulse arrives. The time constant of the elements 5 and 6 should be such that the condenser 5 is substantially discharged before the next squeeg is due to take place.

55 The discharge which spreads along the cathode

3 may be partially stabilised by means of the rectifier 11 which is connected from a suitable tapping point on the battery 8 to the anode 2 through a high frequency choke coil 12.

When the squeeg takes place, a positive potential gating pulse of large amplitude is generated by the cathode 4. This pulse is applied through a resistor 13 and blocking condenser 14 to one corner 15 of a gating rectifier bridge, the diagonally opposite corner 16 being connected to ground through a resistor 17.

The amplitude of the gating pulse is limited by means of the rectifier 18 which is connected from the junction point of elements 13 and 14 to a suitable tapping point on the battery 8. The gating pulses after limitation appear as shown in Fig. 2b. The rectifier 18 cuts off any amplitude variations which might be generated in the tube and which would be liable to introduce noise.

The corners 19 and 20 of the bridge are connected by a series circuit including a battery 21, and the secondary windings of a pulse transformer 22 and of a modulating signal transformer 23. The latter transformer is shunted by a small condenser 24 which by-passes the pulse frequency components.

Triggering pulses with sloping crests like those shown at c, Fig. 2 are supplied to the primary winding of the transformer 22. These pulses are obtained from a local source (not shown) and should have the same repetition frequency as, and should be synchronised with, the pulses shown at a, Fig. 2. The triggering pulses should be applied in positive sense to corner 20 of the bridge. The modulating signal wave, which may be a speech wave, for example, is supplied to the primary winding of the transformer 23.

The potential of the battery 21 should be such that the rectifiers are normally all blocked so that the combined potentials of the triggering pulses and of the modulating signal are insufficient to unblock them. The positive gating pulse generated by the cathode 4 is adapted to overcome the effect of the blocking battery 21 so that the rectifiers 25 and 26 are freed, thus permitting the two transformers to supply a current to resistance 17 through these rectifiers. Positive triggering pulses of the form shown at c Fig. 2 thus appear at corner 16 of the bridge and are supplied through a blocking condenser 27 to a trigger device 28 of any suitable type, adopted to generate at terminal 29 a short pulse, or the leading edge of one, at a time B corresponding to a level such as A, Fig. 2c. The sloping crests of the triggering pulses will be raised or lowered in accordance with the signal potential applied to transformer 23, so that the pulse will be generated by the device 28 earlier or later, (at C or D, for example), as will be well understood by those skilled in the art. The trigger device 28 may be designed to be switched back to the normal condition by the trailing edge E of the triggering pulse, in which case it will generate duration modulated pulses like the one shown at d Fig. 2, having movable leading edges and fixed trailing edges. Alternatively, the device 28 may be designed to generate very short pulses of fixed duration by returning to normal without any external triggering. In this case the pulses generated will be time-phase modulated.

Alternatively, time phase modulated pulses may be obtained by differentiating the leading edges of the pulses d of Fig. 2.

In order to avoid all risk of introduction of noise arising from variations in the operation of

the tube, the leading and trailing edges of the pulses c of Fig. 2 should be arranged to occur slightly later and earlier, respectively, than the leading and trailing edges of the pulses a, as indicated in Fig. 2.

5 The other channel modulators will all be the same as Fig. 1, and may be connected in parallel to the input conductor 30 of the device 28, since all the channel pulses are generated at different 10 times. The phasing of the operation of the respective modulators should be so arranged that gating pulses are generated in turn one at a time.

Fig. 3 shows a demodulator for time-phase modulated pulses. It employs the same kind of 15 tube as that shown in Fig. 1. Elements 1 to 16, 18, 19, 20, 25 and 26 are the same in both figures, and have similar functions.

It will be assumed, as before, that the system 20 is a six channel system, so that there will be six demodulators similar to Fig. 3 the input terminals 25 9 of which are all connected in parallel. The operation of these six demodulators will be differently phased, as in the case of Fig. 1, so that each responds only to the pulses of a given channel.

30 The modulated pulses shown at a, Fig. 4 are applied to terminal 9, Fig. 3, this terminal being connected to the anode 2 through a decoupling resistor 31 in addition to the blocking condenser 30. These pulses are also delayed by a short interval in the delay network 32 and are applied through a decoupling resistor 33 and a blocking condenser 34 to the primary winding of a transformer 35, the secondary winding of which is 35 connected through a blocking battery 36, similar to 21, Fig. 1, to the corners 19 and 20 of the rectifier bridge. These delayed pulses are shown at b, Fig. 4.

The tube 1 counts the incoming pulses in the 40 same manner as in Fig. 1, and generates a gating pulse at the cathode 4 for every sixth incoming pulse. The gating pulses are supplied to the corners 19 and 20 of the bridge through blocking condenser 14 and a transformer 37, the secondary winding of which is connected in series with the secondary winding of transformer 35.

Rectangular timing pulses as shown at c, Fig. 4 are applied through transformer 38 to the corners 15 and 16 of the bridge. When a gating 50 pulse, shown at d, Fig. 4, appears at the same time as one of the delayed pulses b, the rectifiers 25 and 26 are unblocked, as before, and an output pulse e, Fig. 4, will be transmitted from corner 16 through the primary winding of the 55 output transformer 37, which is shunted by an integrating condenser 40. The leading edge of the pulse e coincides with the movable leading edge of the corresponding delayed pulse b, and the trailing edge coincides with the fixed trailing edge of the corresponding pulse c. These output 60 pulses are accordingly duration modulated, and the modulating signal will be recovered from the secondary winding of the transformer 37.

65 Alternatively, the condenser 40 may be omitted and the output pulses may be demodulated by passing them through a low pass filter (not shown) in the usual way.

The delay introduced by the network 32 should 70 be sufficient to ensure that the leading edge of the delayed pulse b which synchronises with the gating pulse d occurs after the latest time of occurrence of the leading edge of this gating pulse, which is likely to vary slightly on account 75 of the variations in the action of the tube. In

this way the introduction of noise by the tube is prevented.

What is claimed is:

1. In an electric pulse communication system having receiving equipment associated with each of n channels, a channel selector comprising a cold cathode gas filled electric discharge tube having a sequence of n discharge gaps including an output gap, arranged as a counter tube, means for applying a train of input pulses to the tube in such manner as to fire the gaps in turn, means for deriving from the output gap a pulse corresponding to each n th input pulse, and means for applying the output pulses as gating pulses to render operative the receiving equipment corresponding to a specified channel.

2. A selector according to claim 1 in which the tube comprises an anode, and co-operating therewith a corrugated cathode having $n-1$ discharge points the first of which is nearer to the anode than the others, and an output cathode forming a sequence of n discharge gaps, means for applying to all the gaps a maintaining potential insufficient to initiate a discharge across any of the gaps, means for applying the input pulses to the anode in such manner as to fire the gaps in succession one at a time, by successive pulses, means for causing the output cathode on firing to squeege and extinguish all the discharges, and means for deriving the gating pulses from the output cathode.

3. A selector according to claim 2 comprising squeeging resistances connected in series between the source of maintaining potential and the anode and output cathode respectively.

4. A selector according to claim 3 in which the resistance corresponding to the output cathode is shunted by a condenser.

5. A selector according to claim 2, comprising means for limiting the amplitude of the gating pulses.

6. A selector according to claim 2, comprising means for stabilising the discharge as it spreads along the sequence of discharge gaps.

7. A modulator for an electric pulse communication system comprising a selector according to claim 1, means for applying a train of saw tooth pulses together with a modulating signal wave through a normally blocked rectifier bridge to a generator of phase modulated pulses, and means for applying the gating pulses periodically to unblock the rectifier bridge.

8. A demodulator for an electric pulse communication system comprising a selector according to claim 1 in which the said input pulses comprise an interleaved train of time modulated channel pulses, means for delaying the input pulses, means for applying the delayed pulses together with a train of regularly repeated timing pulses through a normally blocked rectifier bridge to a pulse demodulator circuit, and means for applying the gating pulses periodically to unblock the rectifier bridge.
